HEATER AND BLOWER ASSEMBLY

Allan E. Beavers, Littleton, and Thurman A. Pelsue, Denver, Colo., assignors to T. A. Pelsue Company, Englewood, Colo.

Filed Oct. 31, 1974, Ser. No. 519,675

Term of patent 14 years

Int. Cl. D23—03

U.S. Cl. D23—73

Fig. 1

Fig. 2

Fig. 3

Fig. 4

Fig. 5

Fig. 6

Fig. 7

FIG. 1 is a perspective view taken from above and to the right of a heater and blower assembly showing our new design;

FIG. 2 is a right side elevation;

FIG. 3 is a top plan view;

FIG. 4 is a left side elevation;

FIG. 5 is a rear elevation;

FIG. 6 is a front elevation; and

FIG. 7 is a bottom plan view.

The electric cord in FIGS. 1 through 3 is shown broken away to indicate indeterminate length. Said cord has been omitted in FIGS. 4 through 7 for ease of illustration.

We claim:

The ornamental design for a heater and blower assembly, as shown and described.
